EMMIT G. LATTA, OF SYRACUSE, NEW YORK.

TYPE-WRITING MACHINE.

1,295,772.

Specification of Letters Patent. Patented Feb. 25, 1919.

Original application filed May 24, 1918, Serial No. 769,581. Divided and this application filed December 13, 1917. Serial No. 207,935.

To all whom it may concern:

Be it known that I, EMMIT G. LATTA, a citizen of the United States, residing at Syracuse, in the county of Onondaga and State of New York, have invented a new and useful Improvement in Type-Writing Machines, of which the following is a specification.

This invention relates to improvements in typewriting machines and more particularly to the means employed in front strike or visible writing typewriters for vibrating and otherwise controlling the action of the ink ribbon. This application is a division 15 of my application on which Patent Number 1,253,258, issued Jan. 15, 1918.

The object of the invention is to provide desirable and practical means of novel and simple construction for this purpose, and to 20 otherwise improve the construction of typewriting machines in the respects hereinafter described and set forth in the claims.

In the accompanying drawings:

Figure 1 is a longitudinal sectional elevation of a typewriting machine embodying the invention, in line 1—1, Fig. 2.

Fig. 2 is a plan view thereof, partly in section, omitting the carriage, and showing a different position of the mechanism for 30 changing the throw of the ribbon vibrator.

Fig. 3 is a fragmentary sectional elevation of the margin stop mechanism, showing the abutment in position to clear the margin stop.

Fig. 4 is a fragmentary transverse sectional elevation of the margin stop mechanism in line 4—4, Fig. 2.

Fig. 5 is a plan view on an enlarged scale, partly in section, of the ribbon vibrating mechanism, showing the parts in the same position as in Fig. 1.

A represents the stationary or main frame; B the paper platen, and C one of the series of pivoted type-bars of the machine. 45 These parts may be of any suitable construction.

As shown, the main frame is provided with a top plate α which is detachably secured in place by screws, or other fastenings. 50 The platen B, as usual, is journaled on a carriage arranged to travel horizontally crosswise of the machine. The complete carriage is not shown, as it is not essential

to an understanding of the invention. It consists of end pieces or frames connected 55 by a base frame or bar b and a front or scale bar b' . b^2 indicates the rack bar on the carriage which meshes with a pinion b^3 connected to the carriage escapement, indicated at b^4 , for controlling the letter space movements of the carriage in the usual way. The type-bars are pivotally mounted in an arc in any suitable way on an upright segment or support c which is fixed in the stationary frame, and are adapted to swing upwardly 65 and rearwardly to make the impressions at the front portion of the platen. Each type-bar is provided with a plurality of type, and the carriage is adapted to be shifted to place the platen in printing relation with one or 70 another of the sets of type on the type-bars.

The platen carriage is supported and adapted to travel horizontally on a shift frame D which is adapted to be shifted up and down for placing the platen in position 75 for printing with one or another of the different sets of type. The shift frame is mounted so as to move substantially vertically up and down by supporting means in the nature of a parallel link motion consisting of upper and lower swinging links, members or parts F and G, each of which is pivoted to the main frame and to the shift frame.

The shift frame D shown consists of an 85 open cradle-like casting of rectangular form which has projections d' d^2 extending, respectively, forwardly and rearwardly from the middle portion of the frame, and is provided with opposed parallel hardened steel 90 race bars or tracks d^3 d^4 between which and complementary race bars or tracks on the base bar b of the carriage are arranged ball bearings b^6 which support the carriage and guide it in its horizontal travel on the shift 95 frame. The front projection d' supports the ribbon guide or vibrator and the carriage escapement is mounted on the rear projection d^2 .

The shifting mechanism shown for moving the shift frame to shift the platen from one to another of its printing positions comprises a shifting cam I which is suitably pivoted at its lower end on the lower rear part of the type-bar segment, and an anti-friction roller i which is suitably journaled

on the leg or member E of the shift frame and enters the cam slot of the cam I. The cam slot has an inclined middle portion for shifting the shift frame and end portions shaped to prevent the shift frame and platen from vibrating at the end of the shift in either direction. K is a horizontal rock shaft which extends transversely of the machine under the key levers and is provided at its central portion with a rigid arm k connected to the cam H by a link k' extending between the two central type-bar hangers or bearings on the segment. The rock shaft is provided at opposite ends with rockers or arms k² which bear and are adapted to rock on the rear ends of shift levers K' which are pivoted between their ends and are provided at their front ends with operating finger keys. When either of the shift keys is depressed the shaft K is rocked and acts through the arm k and link k' to move the cam I rearwardly and force the roller upwardly, thus moving the shift frame support, together with the shift frame and carriage supported thereby from the normal or lower position to the upper or shifted position. A spring k³ coiled about the rock shaft K acts to start the cam from its locked shifted position as soon as the shift key is released, and then the weight of the shift frame and carriage causes the return of these parts to the normal positions. L represents an abutment adapted to be struck by margin stops on the carriage for limiting the horizontal travel of the carriage. l indicates one of the margin stops, two of which are employed, adjustably secured on the front or scale bar b' of the carriage at opposite sides of the abutment. The abutment L is located in a vertical opening l' in the central front projection d' of the shift frame and is fixed to the inner end of a shaft l² which is suitably journaled on the front portion of the shift frame. A spring l³, Fig. 2, coiled about the shaft l² acts to normally hold the front end of the abutment up in line with the margin stops as seen in Fig. 1, and also holds it in the right hand portion of the opening l'. The abutment shaft is provided at its outer end with a rigid arm l⁴ which depends from the shaft in rear of the upright rear end of a rod M which extends forwardly to the keyboard and is provided at its front end with a push key m. By pushing this key rearwardly the rear end of the rod M will engage the arm l⁴ and rock the shaft, thereby lowering the front end of the abutment L out of the path of movement of the margin stops. A suitable spring m', Figs. 1 and 3, returns the push rod M to its normal forward position. The abutment and its shaft shift with the shift frame when the latter is raised or lowered, but the lower end of

the arm l⁴ is opposite the rear end of the push rod M in both positions of the shift frame so that the inward movement of the push key m will move the abutment to clear the margin stops in just the same way in 70 both positions of the shift frame.

N represents a ribbon guide or vibrator mounted to reciprocate vertically on the front projection d' of the shift frame, and n is a vibrator lever for actuating the ribbon 75 vibrator. The vibrator lever is fulcrumed beneath the abutment L in the forked upper end of the leg E of the shift frame and as seen in Fig. 1 has a short horn n' adapted, in one position of the abutment, to be engaged by a depending lug n² on the abutment. In the normal position of the abutment, shown in Figs. 1 and 4, the horn n' on the vibrator lever is located at one side of the lug n² on the abutment, and does not 80 prevent the vibration of the vibrator lever. When, however, the margin stop at the right of the abutment L strikes the latter it moves the abutment to the left against the action of the spring l³, thereby placing the lug n² of the abutment directly over the horn n' of the vibrator lever and locking the vibrator lever against movement. As the vibrator lever is connected to the universal bar which actuates the carriage escapement, as 85 hereinafter described, this locks the carriage escapement, and forms what is commonly known as a line lock to prevent overprinting at the end of a line. If the abutment is lowered to clear the margin stop, as before explained, the spring l³ will return the abutment to the right to its normal position, thereby releasing the escapement or line lock. But the abutment will be held 90 down by the overlying margin stop and a few more characters can be printed, if desired. When the carriage is set back for a new line the spring l³ will return the abutment to its normal elevated position as soon as it clears the margin stop, the abutment thus being ready to again arrest the travel of the carriage. When it is desired to print at the left of the established margin, the abutment is held down by the push key m while the carriage is set over to the right 100 105 as far as desired, and as soon as the carriage has moved back to the left far enough for the abutment to clear the left hand margin stop, the abutment will spring up into normal position ready to lock the line by intercepting the opposite margin stop.

The universal bar O or element for causing the operation of the ribbon vibrator and carriage escapement when the type bars are actuated and the actuators P for the universal bar are arranged much the same as disclosed in Letters Patent No. 1,018,062, granted February 20, 1912, to Oscar C. Kavle, assignor, but instead of the universal bar being mounted on the underside of the 110 115 120 125 130

top plate a , as shown in said patent, the universal bar or rock shaft O is journaled in depending bearing brackets o on the forked head of the leg E of the shift frame, so that the universal bar moves with the shift frame. The actuators P consisting of curved bars arranged over the type-bar bearings in position to be struck and moved by the type-bars when the latter approach the platen, are carried by rods p suitably mounted on the underside of the top plate a to move forwardly and rearwardly. The supporting rods p for the actuators P are provided with upright rear extremities p' 15 adapted to engage the laterally enlarged extremities of arms p^2 depending from the universal bar for rocking the same when the actuators are operated by the type-bars. The extremities p' of the rods p project high enough to engage the arms p^2 and operate the universal bar in both positions of the shift frame. As the arms p^2 are normally out of contact with the actuator rods p there is no friction between these parts 20 when the shift frame is shifted.

Q represents a rearwardly extending arm or lever fixed to the universal bar for actuating the carriage escapement, to which this arm is connected by means not shown, and 25 R represents a lever which is actuated by the arm Q and is connected by a link r to the vibrator lever for operating the latter. The lever R is pivoted at its rear end by a pin or rivet r' to the arm Q and has a hole r^2 30 through which the universal bar passes and which is large enough to receive a sliding sleeve r^3 on the universal bar. This sleeve is adapted to be slid lengthwise on the universal bar to a position in which it projects 35 through the hole r^2 in the lever R and its conical end enters a corresponding recess in the hub of the arm Q . The lever R also has a hole r^4 adapted to receive a fulcrum pin s which is secured to a rod S and extends 40 parallel with the universal bar. The rod S is arranged to slide endwise parallel with the universal bar in guide holes in the brackets o and is provided with a forked collar or part s' which straddles a flange on the 45 sleeve r^3 whereby the sleeve is slid on the universal bar when the slide rod S is moved endwise. The collar s' is fixed on the rod and has a pin s^2 that depends therefrom into a hole in the inner end of a rod s^3 50 which is mounted to move endwise on the underside of the top plate a and is connected by a crank or eccentric t to a rotatable operating shaft T extending to the front of the machine. By turning the shaft T 55 the rod S can be slid to move the sleeve r^3 into and the pin s out of engagement with the lever R , or vice versa. The pin s slides in a fixed lug or bearing s^4 on the shift frame and this prevents the rod S from 60 turning and retains the pin s^2 in the hole in 65

the actuating rod s^3 , and compels the rod S and sleeve r^3 to move lengthwise only as actuated by the shaft T .

s^5 , Fig. 1, indicates a spring connecting the lever R to the shift frame for restoring 70 the universal bar and the connected levers to normal position after actuation. In the position of the parts shown in Fig. 5, the sleeve r^3 is seated in its hole in the lever R and the fulcrum pin s is withdrawn from its hole 75 in the lever. The lever R is then rigidly connected to the arm Q to swing therewith as one part, and produces the proper throw of the vibrator lever to move the lower field or portion of the ribbon to and from printing position. When the slide rod is moved to the position shown in Fig. 2 the lever R will swing on the pin s as a fulcrum, being actuated by the pivot r' connecting it to the arm Q . The hole r^2 in the lever R is large 80 enough to allow the lever to swing on the fulcrum s when the sleeve r^3 is moved out of the hole. The throw of the lever R will then be shortened to the requisite extent to 85 vibrate the upper field or portion of the ribbon to and from printing position. This mechanism thus permits the use of a multi-color ribbon, or ribbon having two different kinds of fields or portions. 90

Since the universal bar, the carriage escapement, the ribbon vibrator and the connections between the same are all mounted on and shift with the shift frame there is no relative movement and friction between the parts when the platen is shifted. This 95 construction also permits all of these parts to remain in place on the shift frame and be removed therewith from the machine. The top plate a of the main frame has an open central portion through which these parts 100 pass when removing the shift frame. The push rod M and actuating rod s^3 remain on the top plate a when the shift frame and the carriage are detached, and when the shift frame is returned the pin enters the 105 hole in the rod s^3 and the arm assumes the proper relation to the push rod M without attention. There is sufficient clearance between the pin and rod s^3 and between the arm l^4 and push rod M to prevent friction 110 between the parts when the shift frame is shifted. 115

I claim as my invention:

1. In a typewriting machine, a rock shaft, means for rocking said shaft at the type 120 strokes, a ribbon vibrator, an arm fixed on said shaft, a loosely mounted arm operatively connected to the ribbon vibrator, means for connecting said two arms rigidly together or loosely at will, and a fulcrum 125 on which said loose arm swings when loosely connected to the fixed arm.

2. In a typewriting machine, a rock shaft, means for rocking said shaft at the type 130 strokes, a ribbon vibrator, an arm fixed on

said shaft, a second arm pivoted to said fixed arm and operatively connected to the ribbon vibrator, a fulcrum for said second arm, and means for freeing said second arm 5 from said fulcrum and rigidly connecting it with said fixed arm.

3. In a typewriting machine, a rock shaft, means for rocking said shaft at the type stroke, a ribbon vibrator, an arm fixed on 10 said shaft, a second arm pivoted to said fixed arm and operatively connected to the ribbon vibrator, a fulcrum for said second arm spaced from said shaft, and means for shifting said fulcrum out of connection with said 15 second arm and rigidly connecting the latter with said fixed arm.

4. In a typewriting machine having a platen carriage, and escapement mechanism therefor, an oscillating universal bar, means 20 for oscillating the universal bar, an arm fixed on said universal bar and operatively connected to the escapement, a second arm adjacent said fixed arm, means for rigidly connecting the two arms together or for 25 loosely connecting them at will, and a ribbon vibrator actuated by said second arm.

5. In a typewriting machine having a platen carriage, and escapement mechanism therefor, a ribbon vibrator, an oscillating 30 universal bar, means for oscillating the universal bar, an arm fixed on the universal bar and operatively connected to the escapement, a second arm operatively connected to the ribbon vibrator and pivotally connected to 35 said fixed arm, and a movable fulcrum for the second arm.

6. In a typewriting machine having a platen carriage, and escapement mechanism therefor, a ribbon vibrator, an oscillating 40 universal bar, means for oscillating the universal bar, an arm fixed on the universal bar and operatively connected to the escapement, a second arm having pivotal connection with said fixed arm and operatively 45 connected to the ribbon vibrator, and a sleeve movable on the universal bar and acting as a detachable connection between the universal bar and said second arm.

7. In a typewriting machine having a 50 platen carriage, an escapement mechanism therefor, and a series of upwardly and rearwardly swinging type-bars, a ribbon vibrator, an oscillating universal bar actuated by the type-bars and operatively connected to 55 the escapement, a sleeve arranged on the universal bar, a loosely mounted arm pivotally connected to the universal bar outside of said sleeve, and means for moving the sleeve along the universal bar for connecting 60 said arm rigidly with the universal bar and for operatively connecting said loosely mounted arm to the ribbon vibrator.

8. In a typewriting machine having a 65 platen carriage, an escapement mechanism therefor, and a series of upwardly and rear-

wardly swinging type-bars, a ribbon vibrator, an oscillating universal bar actuated by the type-bars and operatively connected to the escapement, an arm which has a hole through which said universal bar loosely 70 passes and which is operatively connected to the universal bar beyond said hole, a sleeve slidable on the universal bar, means for holding the sleeve in or out of said hole in the arm, and a fulcrum for said arm when 75 said sleeve is out of said hole in the arm.

9. In a typewriting machine having a platen carriage, an escapement mechanism therefor, a series of upwardly and rearwardly swinging type-bars, and a ribbon 80 vibrator, an oscillating universal bar actuated by the type-bars, an arm fixed on the universal bar and operatively connected to the escapement, and a second arm loosely mounted on the universal bar and operatively 85 connecting said fixed arm to the ribbon vibrator.

10. In a typewriting machine having a platen carriage, an escapement mechanism therefor, and a series of upwardly and rearwardly swinging type-bars, an oscillating universal bar actuated by the type-bars, an arm fixed on the universal bar and operatively connected to the escapement, a ribbon 90 vibrator, a second arm loosely mounted on 95 the universal bar and operatively connecting said fixed arm to the ribbon vibrator, and a movable fulcrum for the second arm.

11. In a typewriting machine having a platen carriage, and escapement mechanism 100 therefor, a ribbon vibrator, an oscillating universal bar, an arm fixed on said universal bar and operatively connected to the escapement, a second arm pivotally connected to said fixed arm and operatively connected 105 to the ribbon vibrator, and means for locking said second arm to the oscillating universal bar at will.

12. In a typewriting machine having a platen carriage, and escapement mechanism 110 therefor, a ribbon vibrator, a series of upwardly and rearwardly swinging type-bars, an oscillating universal bar actuated by the type-bars and having a fixed arm operatively connected to the escapement, and a 115 second arm mounted on the universal bar and forming a lost motion connection with the ribbon vibrator.

13. In a typewriting machine, the combination with key-actuated type-bars, a platen carriage, a ribbon vibrator, and means for actuating the vibrator at the key strokes, of a rocking and longitudinally movable member acting to automatically lock the vibrator at the end of the line, and means extending 120 to the front part of the machine for rocking said member to unlock the vibrator. 125

14. In a typewriting machine, the combination with key-actuated type-bars, a platen carriage, a carriage track, and ribbon vi- 130

brating mechanism actuated at the key strokes, of a sliding rod extending from the central part of the carriage track toward one of its ends and acting to lock the vibrator at the end of the line, and means extending from the outer end of said sliding rod to the front of the machine for rotating the rod to unlock the vibrator.

15. In a typewriting machine, the combination with key-actuated type-bars, a platen carriage, a ribbon vibrator, and means for vibrating the ribbon vibrator at the key strokes, of a member actuated by the carriage to lock the ribbon vibrator at the end of the line and having a rigid rocking extension extending to the side of the machine, and means extending to the front part of the machine for actuating said member to unlock the ribbon vibrator.
- 10 16. In a typewriting machine, the combination with key-actuated type-bars, a platen carriage, a ribbon vibrator, and means for vibrating the ribbon vibrator at the key strokes, of a stop on the carriage, an abutment which engages said stop to arrest the carriage at the end of the line, a rock shaft connected to said abutment and extending substantially in the direction of travel of the carriage, said abutment being moved bodily by said stop to a position to lock the ribbon vibrator, and means for rocking said rock shaft to move said abutment to unlock the ribbon vibrator.

Witness my hand, this 15th day of December, 1917.
